REMOVABLE CONTACTOR CONNECTION PLUG

David Ingalls, Mountainside, and John Wallen Anderson, Westfield, N. J., assignors to Airtron, Inc., Linden, N. J., a corporation of New Jersey

Application January 6, 1950, Serial No. 137,192

9 Claims. (Cl. 339—196)

1

This invention relates to improvements in connection plugs and is particularly useful in such plugs having several contactors permanently associated with the plug and one or more contactors which may readily be associated with or disassociated from the plug as desired.

The term "contactors" is employed herein for convenience as referring to any pin, sleeve or other conducting element which may be held within a connection plug in condition for conducting connection with an extraneous conducting element which may for example be associated with a mating connection plug. The said term also includes adjacent portions of wires soldered or otherwise connected with such conducting elements.

It has been found convenient, in many instances where multi-contactor electric connection plugs are employed, to provide for the plug to accommodate one or more special removable contactors therethrough for wires which may have some special purpose as, for example, for use as thermocouple wires. Where such special contactors are provided in the plug, however, it is sometimes desired to use the plug without such removable connections. Some difficulty has been encountered, however, in constructing such a plug in which the removable contactors are readily removable and yet are rigidly held when associated with the plug.

It is, therefore, an important object of this invention to provide an improved connection plug wherein a certain contactor or contactors therein are capable of being readily associated with or disassociated from the plug, but are nevertheless held firmly in place therein.

Another important object is the provision of a connection plug in which readily removable contactors may be removably associated with the plug, without soldering or equivalent means, while nevertheless being firmly held therein.

Another important object is the provision, in such a plug, of means whereby plural readily removable contactors may be associated unitarily with the plug or may be disassociated unitarily therefrom rather than having to be incorporated into and removed from the plug individually.

Another important object is the provision of a connection plug in which a readily removable contactor or contactors may be associated with or disassociated from the plug without removing or disconnecting other contactors therefrom.

The foregoing objects and other advantages are derived from the present invention, in a broad sense by providing that the removable contactors may be frictionally held within suitably dimensioned grooves in a contactor holding plug or body of material which is sufficiently yieldable

2

to enable a removable contactor to be held tightly within its groove against either lateral or longitudinal displacement and yet be capable of being quickly snapped into or out of the groove. Permanent contactors may be embedded or otherwise fixed within the same contactor holding plug which holds the removable contactors or they may be fixed within a separate contactor holding plug, the latter arrangement yielding certain additional advantages as hereinafter explained.

Three of various possible embodiments of the present invention have been shown, for illustrative purposes, in the accompanying drawing in which:

Fig. 1 is a side elevational view of a multi-contactor connection plug according to the present invention, partly broken away to show certain parts in approximately central longitudinal section, the departure from the central section being indicated by the irregular line 1—1 in Fig. 3.

Fig. 2 is a perspective exploded view of a connection plug of the character illustrated in Fig. 1.

Fig. 3 is an end elevational view of a removable-contactor holding body in the form of a ring for holding two readily removable contactors in a device according to the embodiment of the present invention illustrated in Figs. 1 and 2; the said contactors and several fixed contactors being shown in cross-section to show the manner in which they are accommodated by the mentioned ring.

Fig. 4 is a view substantially like Fig. 3, but showing a modified form of ring for holding two readily removable contactors.

Fig. 5 is a side elevational view of a supplemental ring or washer for use in association with the ring illustrated in Fig. 4.

Fig. 6 is a perspective exploded view of certain parts of a further modification of the invention in which the plug which holds the fixed contactors also includes means for frictionally holding the readily removable contactors; this view omitting the shell and locking means of the device, but including a ring or washer adapted to complement the contactor holding ring.

The embodiment illustrated in Figs. 1-3 inclusive includes a substantially cylindrical mounting shell 11 having a mounting flange 12 provided with suitable screw holes 13 by which the shell may be secured to a panel 14. One end of the shell is threaded as at 15 to receive a cup-shaped, knurled locking nut 16 which serves to hold together as a unit the various plug portions hereinafter described. The other end of the shell may also be threaded as at 17 to receive a suitable coupling nut (not shown) by which a mating

plug (not shown) may be held in connected association with the plug which embodies the present invention.

Within the shell 11, a fixed-contactor holding body in the form of a cylindrical main plug 18 of dielectric, and preferably molded material may have a plurality of fixed contactors 19 firmly embedded therewith and extending axially therethrough from the front end of the plug to the back end thereof where connection portions 19a of said contact members may receive wires 20, the ends of which may be fixed to the connection portions of the contactors by soldering or other suitable means.

As the parts appear in Figs. 1 and 2, the plug 18 which is insertable into the shell 11 from the right end thereof bears at its left end against an annular shoulder 21 in the shell and is locked in place thereagainst by a locking ring 22 which snaps into an annular groove 23 in the shell. The inside of the shell and the outside of the plug 18 are respectively provided with an axially extending rib 24 and an axially extending groove 25 to prevent rotation of said plug within the shell. A notch 26 in the right end of the shell, in axial alignment with the rib 24, aids in locating the said rib and the groove 25 in axial alignment when the device is being assembled; and the said notch is useful also in aiding in the removal of the locking ring 22 if it should ever be desired to entirely disassemble the device.

It may be observed that the plug 18, in the embodiment illustrated in Figs. 1-3, is provided with two axially extending passages 27, 28 for permitting the sliding extension therethrough of two readily removable contactors 29, 30 which respectively are formed with somewhat thickened mounting portions 31, 32. Ordinarily, the several contactors 29, 30 have portions at or adjacent to their mounting portions which are of different shapes or of different cross-sectional dimensions and each of the passages 27, 28 is complementally shaped with respect to one only of the said contactors so as to assure that the latter will be associated with their proper passages in the plug.

A removable-contactor holding body in the form of a ring 33, which may conveniently be molded of dielectric material such as phenolic resin or other suitable molded material, is formed with a relatively large axial opening or passage 34 for loosely accommodating therewithin the several wires 20 which are connected to the fixed contactors. The passage 34 includes one or more axially extending, removable-contactor holding grooves 35 opening at one side thereof into the said passage. As the embodiment illustrated in Figs. 1-3 includes or provides for two readily removable contactors 29, 30, two grooves 35 are provided therein.

The mounting portions 31, 32 of the two removable contactors are each formed with an annular groove 36 which is only slightly longer than the thickness of the ring 33, and the mounting portion, at the bottom of said groove in each contactor, is of a thickness corresponding approximately to the diameter of a particular groove 35 with which that contactor is to be associated. The grooves 35 are formed with axially extending side openings, each of which, preferably, but not necessarily, is slightly narrower than the mentioned thickness of an associated contactor 29 or 30, at the latter's groove 36. With the parts thus dimensioned, a contactor 29 or 30 can readily be fixedly associated with the

ring 33 by extending it into the opening 34 sufficiently to bring its groove 36 into radial alignment with the said ring after which the said contactor may be moved laterally outwardly to bring the grooved part of its mounting portion into the groove 35 with which it is intended to be associated.

Because of the mentioned relative dimensions of the various described parts, a contactor 29 or 30, by the described lateral movement, enters its related groove 35 by slightly wedging apart or deforming the side opening of said groove. However, as the ring 33 is preferably formed of somewhat flexible material, a slight reverse deformation of the side opening of the groove 35 occurs after the contactor has entered said groove, thereby firmly holding the contactor against unintended lateral displacement. Also, the opposite walls defining the annular grooves 36 in the contactors 29, 30 overlie portions of the opposite faces of the ring 33 whereby the said contactors are prevented from shifting axially relatively to the ring.

In structures according to this invention, wherein the side opening of a groove 35 is not narrower than the diameter of the groove, the resiliency of the material of the ring 33 will cause the removable contactors to be held firmly against unintended lateral displacement.

As best seen by comparison of Figs. 1 and 2, a ring 33 with one or more readily removable contactors held therein may be moved axially so that the said contactors will each extend through and be supported by one of the axially extending passages 27, 28 in the plug 18. The parts of the device are so proportioned that when the ring 33 is moved into close juxtaposition to the plug 18, all the contactors, both fixed and removable, preferably extend so that their ends come substantially within a common transverse plane located inwardly of the outer edge of the end portion 15 of the shell. When the plug 18 and the ring 33, with their respective contactors, are thus brought together they are held together by a radial flange 31 of the nut 16, which overlies the end face of the ring 33.

In order to understand fully the manner in which certain contactors may readily be associated with or disassociated from the described connection plug, it may first be assumed that at the time the several wires 20 are soldered to their related fixed contactors 19, the said wires were extended through the nut 16 and the ring 33 while the two latter were temporarily disassociated from the remainder of the device. Then, after connection of the wires 20 to their related contactors, the ring 33 was moved axially along said wires into the shell and into close juxtaposition with the plug 18 after which the nut 16 was also moved along said wires and threaded onto the threaded portion 15 in order to hold all the parts of the device in assembled relationship.

Let us suppose that, with the plug and wires in the assembled condition described in the preceding paragraph, it is desired to insert two additional wires and related contactors into the plug, possibly for some special purpose. In order to readily insert such additional wires and contactors, the nut 16 is unthreaded from the portion 15 of the shell, after which said nut is slid back along the wires 20 which it encircles. Then, the ring 33 is also slid back along the wires 20 which it likewise encircles. Then, the additional wires, having previously been soldered or otherwise

connected to their related contactors, are first passed leftwardly, as viewed in the drawings, through nut 16 and partially through the passage 34 in the ring 33. When the annular groove 36, in the mounting portions of a contact member then being inserted, is in radial alignment with the ring 33, the said mounting portion is moved laterally outwardly and snapped into its proper groove 35 in the ring 33. The same procedure is followed with an additional contactor.

After the additional contactors are disposed firmly within the ring 33, the latter is moved axially leftwardly so that the said contactors will extend into or through the passages 27, 28 in the plug 18. Then, the nut 16 is slid along the wires and threaded onto the threaded portion 15 of the shell in the manner already described. This results in the removable contactors as well as the fixed contactors being firmly held within the connection plug. When it is desired to remove one or more of the removable contactors and their associated wires, it is necessary only to pursue the reverse of the operation just described.

The ring for holding the removable contactors need not necessarily be of the form shown in Fig. 3, but, instead, may be of a form such as illustrated in Fig. 4 wherein a ring 33a is provided with a large opening or passage 34a for accommodating permanent or fixed wires 20 therewithin. However, the ring 33a instead of having internal grooves 35, may be formed with external, axially extending grooves 35a for the same purpose. The only difference in the use of the device, when the ring 33a is employed instead of the ring 35, is that the removable contactors are snapped into and out of the grooves 35a from the exterior of the ring 33a rather than from the interior thereof.

When a ring such as ring 33a is employed, it is desirable to employ with it a washer 38 of dielectric material, as shown in Fig. 5, having an opening 38a for enabling all the contactors to pass therethrough and having on one side thereof an axially extending lip 38b which overlies the side openings of the grooves 35a thereby providing a dielectric portion to insulate the removable contactors from the shell at the point where those members extend through the ring 33a. The washer 38, of course, is held in its described intimate association with the ring 33 by the lock nut 16.

The embodiment illustrated in Fig. 6 differs from those hereinbefore described chiefly in that no separate ring comparable to rings 33 or 33a is provided. Instead, a plug 18a not only has wires 20 and related contactors fixedly associated therewith, but also is provided with axially extending grooves 35b having side openings at a plane peripheral face 18b of the plug for holding removable contactors 29, 30. The removable contactors may be readily snapped into or out of the grooves 35b in the same manner as with grooves 35a in the embodiment illustrated in Fig. 4. The grooves 35b may have transverse, arcuate grooves 40 formed therein and the mounting portions of the removable contactors may be formed with integral radial flanges 41 which seat within the grooves 40 to prevent axial shifting of said contactors.

The embodiment of Fig. 6 includes a washer 39 of dielectric material having an opening 39a and an axially extending lip 39b which, when the device is assembled, overlies the face 18b, thereby providing insulation for the removable contactors at the point where they pass through the plug

18a. The washer 39 and the plug 18a are held in their described assembled relationship within a suitable shell, by a nut such as nut 16.

It should be apparent that when it is desired to insert or remove additional contactors in the embodiment of Fig. 6, all contactors, both fixed and removable are necessarily handled, as the plug 18a must be removed from its shell to make the desired contactor changes. This may be satisfactory in some cases and unsatisfactory in other cases. Hence, the other illustrated embodiments may sometimes be preferred as in those embodiments, the plug 18 need not be removed in effecting contactor changes.

15 It should be understood also that when a lipped washer such as washers 38 or 39 is employed, the fit of the removable contactor within its related groove need not be friction tight, as the parts can be so proportioned that the lip of the lipped washer will hold the contactor firmly within its related groove against lateral displacement. Likewise, in an inner groove arrangement as illustrated in Figs. 1-3, the fit of a removable contactor within its related groove need not be friction tight as a blocking ring or other suitable barrier member may be arranged within the ring 33 or equivalent member to function like the lips 38b, 39b to hold the contactor within its related groove against lateral displacement.

20 30 Although the present invention has been illustrated and described with reference to a connection plug having contact pins as male connectors, nevertheless it should be understood that the present invention may be employed also in a connection plug having contact sleeves as female connectors. It should also be understood that the present inventive concept may be employed in various connection plug structures other than those described herein and illustrated in the accompanying drawings and that this invention, therefore, is not limited to such disclosed and described embodiments, but is to be considered as a breadth substantially corresponding to the following claims.

35 45 What we claim is:

1. A multi-contactor connection plug comprising a tubular shell, a fixed contactor carrying plug immovably held within said shell, a removable contactor carrying plug disposed within said shell in end to end relation to the first mentioned plug and being formed with an axial passage therethrough and one or more axially extending removable-contactor holding grooves into each of which a removable contactor may be laterally 50 pressed and be held therewithin, a centrally apertured nut coaxing with said shell to hold the second of said plugs within the latter, and plural fixed contactors fixedly disposed in axially-extending positions within the first mentioned plug 55 in axial alignment with the said passage in the second mentioned plug, the first mentioned plug being formed with one or more axially extending openings which, in one angular relationship of the two plugs, are in axial alignment with said 60 one or more grooves so that contactors held by said grooves may extend into the said openings.

65 70 75 2. A multi-contactor connection plug according to claim 1, further including one or more removable contactors each having a mounting portion formed with a peripheral groove, the thickness of the removable contactor at said peripheral groove being substantially similar to the diameter of a related axially extending groove in the second mentioned plug and the width of said peripheral groove being only slightly greater than

the axial dimension of the said second mentioned plug at the latter's said axial groove, whereby to enable a removable contactor to be held by said second mentioned plug against displacement either laterally or axially.

3. A multi-contactor connection plug comprising a tubular shell, a first plug immovably held within said shell, a second, readily removable plug within said shell, in end to end relation to the first plug and having an axially extending opening and one or more axially extending, contactor-holding grooves formed in said second plug, plural axially extending connectors fixed to said first plug in axial alignment with said opening to permit extension of said connectors therethrough, and one or more axially extending passages in said first plug in axial alignment with said grooves, whereby connectors held within said grooves may telescope into said passages in the first plug.

4. A multi-contactor connection plug according to claim 3, the said grooves opening laterally into the said axial opening in the second plug.

5. A multi-contactor connection plug according to claim 3, further including removable connectors frictionally held within said grooves and extending into said axial passages in the first plug; the conformations of the several removable connectors being different from each other, and the said axial passages and grooves being disposable in pairs each having conformations enabling each pair to receive only a certain one of said removable connectors.

6. A multi-contactor connection plug according to claim 3, the said grooves opening laterally into the outer periphery of the second plug.

7. A multi-contactor connection plug according to claim 6, the said second plug having a flat at one peripheral portion and the grooves in said second plug opening laterally at said flat, the device further including a washer having an axially extending insulating lip at one circumferential portion, overlying said flat and insulating the contactors in said grooves from the shell.

8. A connection plug assembly comprising a tubular shell having an outer end to which a mating connection device may be connected and an inner end through which contactors are introduced for fixed association with said assembly as a part thereof; a first, dielectric, cylindrical, contactor-holding block fixed within said shell and having plural apertures extending axially therethrough for receiving outer ends of elongate contactors introduced axially into said shell from the latter's inner end; plural elongate contactors each having an outer end portion extending with substantially accurate fit within one of said apertures, an intermediate circumferential enlargement in abutment with said first block marginally of the contactor's related aperture to limit the contactors' outward movement in their respective related apertures, and an inner end portion; a second, dielectric, cylindrical, contactor-holding block, readily removably disposed at the inner end of said shell in axial alignment with said first block and adjacent the latter's inner end and having plural, axially extending, laterally opening slots therein through which extend the inner end portions of the contactors, portions of which slots are in alignment axially with said apertures in the first block in one angular position of the second block and marginal portions of which slots, which, when the said second block is in its said one angular position, are in axially aligned abutting relation to

the said enlargements whereby to hold the contactors against dislodgment from the first block; and a centrally apertured nut threaded upon the inner end of the shell and having a portion coacting with the second block as a sole means for positively but readily removably holding the second block in its said adjacency to the inner end of the first block.

9. A connection plug assembly comprising a tubular shell having an outer end to which a mating connection device may be connected and an inner end through which contactors are introduced for fixed association with said assembly as a part thereof; a first, dielectric, cylindrical, contactor-holding block disposed within said shell toward the outer end thereof and having plural apertures extending axially therethrough for receiving outer ends of elongate contactors introduced axially into said shell from the latter's inner end; means within the shell and coacting with said first block to hold the latter against axial movement relatively to the shell; plural elongate contactors each having an outer end portion extending with substantially accurate fit within one of said apertures, an inner end portion and an intermediate circumferential enlargement in abutment with said first block marginally of the contactor's related aperture to limit the contactor's outward movement in said related aperture; a second, dielectric, cylindrical, contactor-holding block disposed within said shell in axial alignment with said first block and adjacent the latter's inner end and being removable from said shell at the latter's inner end and having plural, axially extending, laterally opening slots therein through which extend the said inner end portions of the contactors, portions of which slots are in alignment axially with said apertures in the first block in one relative angular relationship of the two blocks and marginal portions of which slots, which, when the blocks are in their said one relative angular relationship, are in axially aligned abutting relation to said enlargements whereby to hold the contactors against dislodgment from the first block; and a centrally apertured nut threaded upon the inner end of the shell and having a portion coacting with the second block as sole abutting means for positively but readily removably holding the second block within the shell in its said adjacency to the inner end of the first block.

DAVID INGALLS.
